[57] CLAIM

The ornamental design for an optical disk drive module, as shown and described.

DESCRIPTION

FIG. 1 is a top and left front respective view of an optical disk drive module with the door in the open position, showing my new design;

FIG. 2 is a top, right, front perspective view thereof, the door in the closed position;

FIG. 3 is a rear, left side perspective view; and

FIG. 4 is a front elevational view thereof on an enlarged scale, the door in the opened position.

FIG. 1

FIG. 2

FIG. 3

FIG. 4
